UNITED STATES PATENT OFFICE.

FRED G. STONE, OF MANCHESTER, NEW HAMPSHIRE, ASSIGNOR TO STONE SURFACE WASHER COMPANY, INC., OF NORTH ANDOVER, MASSACHUSETTS, A CORPORATION OF MASSACHUSETTS.

SURFACE WASHER.

Application filed July 3, 1926. Serial No. 120,373.

This invention relates to certain improvements in the surface washer disclosed by my Patent No. 1,587,873, dated June 8, 1926.

The said patented washer comprises a water-receiving head, a water-delivering head, and a water-conducting neck, connecting said heads and spacing the same apart, so that portions of an operating hand may be inserted therebetween, the neck being formed to engage fingers of a hand interposed between the heads, the delivering head having a perforated front wall, and a back wall constituting a rest for portions of the hand and formed to permit flexure of the fingers and thumb across its margin, so that an applicator, such as a sponge, may be confined by the fingers and thumb in contact with the perforated front wall of the delivering head, to receive water from the latter and permit the application of the saturated applicator to a surface to be washed, while the washer and applicator are controlled by the operating hand.

The object of the invention is to provide an improved three-part construction of the washer, each of the parts being adapted to be formed from suitable metal by die casting.

The invention is embodied in the improvements hereinafter described and claimed.

Of the accompanying drawings forming a part of this specification,—

Figure 1 is a side view of a surface washer embodying my improvements.

Figure 2 is an end view of the same.

Figure 3 is a section on line 3—3 of Figure 2.

Figures 4, 5, and 6 show in section, and separated from each other, the three parts of the washer shown by the preceding figures.

Figure 7 is a section on line 7—7 of Figures 1 and 2.

Figure 8 is a view similar to a portion of Figure 3, showing a modification.

The same reference characters indicate the same parts in all of the figures.

My improved surface washer comprises a water-receiving head 12, of cast metal, preferably aluminum, having an end portion 12^a formed to be engaged with a flexible hose supplying water to the washer. Cast integral with the head 12 is a water-conducting neck, composed of an annular body member 13, provided with an internal annular groove

14, communicating through a passage 15 with the bore of the head 12. The annular body member is provided at one side of the groove with an annular seat 16, and at the opposite side of the groove with an internal screw-thread 17. A separately formed annular closing member, adapted to cover the groove and form therewith an annular conduit, is composed of a tube or bushing 18, provided at one end with an external screw-thread 19, engaging the internal thread 17, and at its opposite end with a flange 20 bearing on the seat 16. The bore of the bushing 18 forms a finger-receiving opening 21, adapted to receive the finger 22 of the operating hand shown by dotted lines in Figure 1, the external form of the body portion 13 of the neck being such that it conforms to the natural divergence of two adjacent fingers 23, as indicated by Figure 7.

The bore of the bushing 18 may be engaged with an expansible mandrel, so that the bushing may be turned by the mandrel and screwed into the internal thread 17, this operation pressing the flange 20 against the seat 16, so that water-tight joints are formed.

The washer comprises also a delivering head composed of a rigid back member 24, cast integral with the body member 13, and a separately formed perforated flexible front member 25, having a water-tight connection 26 at its margin with the back member 24, and forming therewith a water chamber 26, communicating through a passage 27 with the conduit in the neck.

The said water-tight connection is preferably provided by the construction next described.

I provide the back 24 with a central outwardly projecting boss 28, having a tapped socket 29. I also provide the back with an annular inwardly facing shoulder 30, surrounding and spaced from the boss 28. The front member 25 is a concavo-convex disk, formed at its margin to bear on the shoulder 30, and having a central orifice 31, coinciding with the boss socket 29. The curvature of the front member 25 is such that when it is first applied, its margin being seated on the shoulder 30, the central portion of the front member is slightly separated from the outer end of the boss. The headed clamping screw 32 is then inserted in the orifice 31 and socket 29, and turned

until the pressure of its head on the central portion of the front member 25 flexes said member to expand its margin and press the same against the annular shoulder 30, thereby forming a water-tight connection between the margin of the front member 25, and the back member 24.

The arrangement is such that an applicator 33, such as the sponge shown by dotted lines in Figure 1, may be confined against the perforated front member 25, by the flexed fingers and thumb of an operating hand, the conducting neck, connecting the receiving and delivering heads, being suitably engaged with the hand, so that the operator is enabled to conveniently and effectively control the washer and the applicator.

The receiving-head 12 may be provided, as shown by my above-mentioned patent, with an outwardly directed nozzle 34, adapted to emit a jet 35 of water beside the operating hand, and without contact therewith, the nozzle being provided with a soft rubber cap 36, locatable thereon and constituting a buffer and a valve, whereby the nozzle may be opened and closed, the nozzle having an outlet slot 37, coinciding with an outlet slot 38, formed in one side of the cap 36. The nozzle 34 may be omitted, as indicated by Figure 8.

I claim:

1. A three-piece surface washer comprising a water-receiving-head of cast metal, a water-conducting neck composed of an annular body member cast integral with the receiving-head and provided with an internal annular groove communicating with the receiving-head, an internal annular seat

at one side of the groove, and an internal screw-thread at the opposite side of the groove, a separately formed annular closing member covering the groove and forming therewith an annular conduit, said closing member forming also a finger-receiving opening and being provided at one end with an external screw-thread engaging said internal thread, and at its opposite end with a flange bearing on said seat, and a delivering-head composed of a back member cast integral with the body member of the neck, and a separately formed perforated front member having a water-tight connection with the back member, and forming therewith a water-chamber communicating with the neck.

2. In a surface washer, a water-delivering head comprising a rigid back member provided with a central outwardly projecting boss having a tapped socket, and with an annular inwardly facing shoulder surrounding and spaced from said boss, a concavo-convex perforated flexible front member formed at its margin to bear on said shoulder and having a central orifice coinciding with the boss socket, and a headed clamping-screw inserted in said orifice and engaged with said socket, the screw securing the front member to the boss, and flexing the front member to expand its margin and press the same against the annular shoulder, thereby forming a water-tight connection between the margin of the front member and the annular shoulder of the back member.

In testimony whereof I have affixed my signature:

FRED G. STONE.
